SPIKE PULLER

Marvin B. Alley, Birmingham, Ala.

Application February 5, 1944, Serial No. 521,188

9 Claims. (Cl. 254—21)

This invention relates to railroad track spike pullers and has for its object to provide a tool of the character designated which shall be operable from one side of a rail to pull spikes on both sides and which shall include means to afford a compound leverage for the initial or starting pull on a spike.

A further object of my invention is to provide a spike puller which shall be operable to provide a compound pulling leverage in starting to pull a spike and a more rapid, direct leverage after the spike is started.

A still further object of my invention is to provide a railroad spike puller which shall be operable from one side of a rail to pull spikes on both sides thereof and which shall include means to adjust the device to operate with rails of different sizes.

As is well known in the art to which my invention relates, the tool usually employed for pulling railroad spikes is the ordinary claw bar. Such a tool provides an initial powerful leverage for starting a spike, but once the spike is started, an additional fulcrum member must be provided in order to complete the pulling action. Also, the claw bar is at a disadvantage in pulling spikes from rails located in tunnels or adjacent to any structure having a relative close clearance with respect to the rails. In accordance with my invention, I provide a spike puller which embodies a separate pulling head operable from either side of a rail and which includes compound lever means for the initial or starting pull on the spike, with a direct leverage pull after the spike has been started.

A device embodying features of my invention is illustrated in the accompanying drawings forming a part of this application, in which;

Fig. 1 is a sectional elevation showing my improved spike puller in position to pull a railroad spike from the side of the rail opposite the operator;

Fig. 2 is a similar view showing the device in position to pull a spike from the same side of the rail as the operator;

Fig. 3 is a view similar to Fig. 1 showing the initial or starting pull on a spike;

Fig. 4 is a front elevational view looking in the direction of the arrows IV—IV in Fig. 1, with the rail and spike indicated in dotted lines and showing the manner in which the spike is engaged by the pulling elements;

Figs. 5 and 6 are a side elevation, and an end view, respectively, of one of the detachable claws or pulling elements drawn to an enlarged scale;

Fig. 7 is a side elevational view of a liner for varying the spacing of the pulling elements also drawn to an enlarged scale; and

Figs. 8 and 9 are side and front views, respectively, of the pulling head separate from the other parts.

Referring now to the drawings for a better understanding of my invention, I show in Figs. 1 to 4 inclusive a railroad rail 10 held in place by spikes 11 and 12 driven into a cross tie 13. My improved spike pulling device is shown in position to pull the spike 12, operating from the side of the rail 10 opposite the spike. It comprises a pulling head 14 which is generally C shaped in side elevation and comprises spike engaging elements, or claw members, 16 and 17, detachably secured to the lower end thereof and a lever arm 18 rising upwardly and inclined to overhang the lower end of the pulling head. The upper end of the lever arm 18 is slotted at 19 (see Fig. 9).

At the lower end of the pulling head 14 is a lug 21 having spaced holes 22 and 23 therein to which are connected a pair of links 24 and 26 by means of a bolt 27. The upper ends of the links 24 and 25 26 are connected to the lower end of a lever 28 which is provided with an offset member 29 at its lower end having spaced holes 30 and 31 therein for receiving a bolt 32. The lever 28 as shown is relatively short and may be extended to any 30 desired length by attaching a piece of pipe as is well understood. By means of the spaced holes in the lug 21 and in the lever, I am enabled to adjust the apparatus for operation with different, size rails. The spike engaging, or claw, elements 35 16 and 17 are preferably made detachable and made of hardened steel so that they may be renewed when damaged or worn. They are adjustable laterally with respect to each other by means of liners 33 (see Fig. 7) which further adapts the 40 apparatus for use with spikes of different sizes.

An important feature of my invention resides in the provision of a heel or fulcrum member 34 on the pulling head 14 closely adjacent the claws or spike engaging elements 16 and 17. When 45 pulling a spike from the position shown in Fig. 1 the claw members 16 and 17 are engaged with the spike 12 and the lever 28 is placed in the position shown. In this position, an inclined surface 36 on the end of the offset position 29 of the lever 28 bears against the upper end of the lever arm 18 of the pulling head and the offset portion 29 of the lever 28 rests on the rail 10 as a fulcrum. It will be seen that when the lever 28 is moved in the direction shown by the arrow, the surface 50 36 first co-acts with the upper end of the lever 55 36

arm 18 to rock the pulling head 14 about its fulcrum 34 to the position shown in Fig. 3 of the drawings. This provides the powerful necessary compound leverage for starting the spike. With a further downward movement of the lever 28, the spike 12 is pulled by the direct action of the lever 28 resting on the rail 10 as a fulcrum. With exceptionally long spikes, it may be necessary to have a wider range of movement of the pulling head 14 and this is provided for by means of a protuberance 37 on the back of the lever 28 which may be placed on the rail 10 after the spike 12 has been started so that it may be raised higher by downward movement of the lever 28.

When pulling the spike 11 from the same side of the rail as the operator, the pulling head 14 is placed in the position shown in Fig. 2 with the claws or pulling elements 16 and 17 engaged with the spike 11 and with the lever 28 in the position shown, that is to say, approaching the vertical. In this position, the flat surface 38 on top of the offset portion 29 of the lever 28 is engaged with the upper end of the lever arm 18 on the pulling head, and the opposite side of the portion 29 is bearing against the rail 10. As the lever 28 is moved in the direction shown by the arrow in Fig. 2, the offset portion 29 of the lever 28 co-acting between the rail 10 and the upper end of the pulling head exerts a powerful force against the upper end of the lever arm 18 to rock the pulling head about its fulcrum 34 and provide the necessary powerful initial starting pull on the spike 11. As the lever 28 is moved further, it enters the slots 19 in the upper end of the lever arm 18 and as the lever 28 is moved downwards the pulling head 14 is rocked further in the direction shown until its rear curved surface 39 engages the tie 13 and acts as a fulcrum for the more rapid extraction of the spike 11.

From the foregoing it will be apparent that I have devised an improved railroad spike puller which is sturdy, simple of construction and operation, one which is adapted to operate from one side of a rail in pulling spikes from both sides thereof, and one which is adapted to exert a powerful initial pulling force in extracting a spike.

My invention is especially important for use in coal mines where the tracks are often laid in close proximity to the walls of tunnels and drifts. Also where electric motive power is employed, the bare wires for conveying the electric current are usually placed along one side of the tunnels, making it extremely dangerous for a workman to employ an ordinary claw bar on that side. As may be seen from the foregoing description, all the spikes may be pulled by means of my invention with the workman operating from between the rails, without any danger of coming in contact with the electric current bearing wires.

I wish it to be understood that I do not desire to be limited to the exact details of construction shown and described, for obvious modifications will occur to a person skilled in the art.

What I claim is:

1. A tool of the character described comprising a generally C shaped pulling head, spike engaging claws at the lower end of the pulling head, the upper end of the pulling head overhanging the claws, and a lever operatively connected to the lower end of the pulling head and adapted to take a bearing against the upper end of the pulling head and rock it about its lower end to effect an initial pull on a spike.

2. In a spike puller, a pulling head including spike engaging means, a fulcrum member closely

adjacent thereto, a lever arm extending upwardly from the spike engaging means, and a relatively long lever flexibly connected to the pulling head and having a projection adapted to bear against the lever arm and move the pulling head about its fulcrum member in starting to pull a spike.

3. In a tool for pulling spikes holding a railroad rail, a pulling head including spike engaging means, a fulcrum member closely adjacent thereto, a lever arm extending upwardly and inclined to overhang the spike engaging means, a relatively long lever flexibly connected to the pulling head and adapted to take a purchase on the rail as a fulcrum in pulling a spike, a projection on the relatively long lever adapted to bear against the upper end of the lever arm on the pulling head as the long lever is moved about its fulcrum and move the pulling head about its fulcrum member when starting to pull a spike.

4. In a tool for pulling spikes holding a railroad rail, a pulling head having spike engaging claws on the lower end thereof and inclined upwardly toward the rail, a relatively long lever adapted to bear on the rail as a fulcrum and having a projection adapted to bear against the upper end of the pulling head, and a link connecting the long lever to the lower end of the pulling head.

5. A tool as defined in claim 4 in which the spike engaging means is comprised of detachable members adjustable as to distance apart.

6. A tool as defined in claim 4 in which the length of the link is adjustable to accommodate the tool to rails of different heights.

7. In a tool for pulling spikes holding a railroad rail, a pulling head having spike engaging claws on the lower end thereof and inclined upwardly so that its upper end overhangs the spike engaging claws, a lever adapted to coact between the upper end of the pulling head and the rail and move the upper end of the pulling head in a direction away from the rail, a fulcrum member on the pulling head closely adjacent to the spike engaging claws, and link means flexibly connecting the lever to the pulling head.

8. In a tool for pulling spikes holding a railroad rail, a pulling head having spike engaging claws on the lower end thereof and inclined upwardly so that its upper end overhangs the spike engaging claws, a lever adapted to coact between the upper end of the pulling head and the rail and move the upper end of the pulling head in a direction away from the rail, a fulcrum member on the pulling head closely adjacent to the spike engaging claws, link means flexibly connecting the lever to the pulling head, and a protuberance on the lower end of the lever for engaging the rail and acting as a fulcrum after a spike is started to complete the pulling thereof.

9. In a tool for pulling spikes holding a railroad rail, a pulling head having spike engaging claws on the lower end thereof and inclined upwardly so that its upper end overhangs the spike engaging claws, a lever adapted to coact between the upper end of the pulling head and the rail and move the upper end of the pulling head in a direction away from the rail, a fulcrum member on the pulling head closely adjacent to the spike engaging claws, link means flexibly connecting the lever to the pulling head, and other fulcrum means more remote from the spike engaging claws for completing the pulling of a spike after it is started.
